US00D767618S

(12) **United States Design Patent** (10) **Patent No.:** **US D767,618 S**
(45) **Date of Patent:** **** Sep. 27, 2016**

(54) **DISPLAY SCREEN WITH GRAPHICAL USER INTERFACE**

(71) Applicant: **Microsoft Corporation**, Redmond, WA (US)

(72) Inventors: **Kathryn Stone Perez**, Seattle, WA (US); **Sebastian Andreas Sheldon Grinke**, Kirkland, WA (US); **Kristie Joy Fisher**, Redmond, WA (US); **Mathew Lee McInelly**, Redmond, WA (US); **Dana Ludwig**, Redmond, WA (US); **Roy Lewis Herrod**, Seattle, WA (US); **Jason Micheal Hewitt**, Redmond, WA (US); **Jeffrey Scott Blazier**, Sammamish, WA (US)

(73) Assignee: **Microsoft Corporation**, Redmond, WA (US)

(**) Term: **14 Years**

(21) Appl. No.: **29/469,613**

(22) Filed: **Oct. 11, 2013**

(51) LOC (10) Cl. **14-04**

(52) U.S. Cl.

USPC **D14/488**

(58) **Field of Classification Search**

USPC D14/485-495
CPC .. G06F 3/0481; G06F 3/0482; G06F 3/0488;
G06F 3/04817; G06F 3/04883

(57) **CLAIM**

The ornamental design for a display screen with graphical user interface, as shown and described.

DESCRIPTION

The FIGURE is a front view of a display screen with graphical user interface showing our new design.

The broken line showing of the tiles, the remainder of the graphical user interface, and the remainder of the display screen illustrates the environment of the claimed design and forms no part of the claim.
